UNITED STATES PATENT OFFICE.

EDOUARD BERTRAND, OF BROOKLYN, NEW YORK.

ORNAMENTING FUR.

SPECIFICATION forming part of Letters Patent No. 242,742, dated June 14, 1881.

Application filed May 13, 1881. (No model.)

To all whom it may concern:

Be it known that I, EDOUARD BERTRAND, a citizen of France, residing at Brooklyn, in the county of Kings and State of New York, have 5 invented new and useful Improvements in Ornamenting Fur, of which the following is a specification.

This invention consists in an improved method of ornamenting fur by attaching to its 10 skin tufts of fur of a different color, the hair of the body fur or pelt being pressed out of the way so as to expose the bare skin and allow of securing the tufts thereto without injuring or disarranging its hairs; also, in a clamp 15 composed of a fixed jaw and a movable jaw, which is pivoted at one end to the stationary jaw and lined on its inner surface with sand-paper or other equivalent rough material, so that if a piece of fur or pelt is placed upon the stationary 20 jaw with its hair outside and the movable jaw is turned down the hairs of the pelt are drawn down and firmly retained by said movable jaw, and the bare skin is exposed for attaching thereto the tufts of fur of a different 25 color.

This invention is illustrated in the accompanying drawings, in which Figure 1 represents a transverse section of the jaws of my clamp with a piece of fur between them. Fig. 30 2 is a perspective view of the clamp on a smaller scale than the previous figure. Fig. 3 is a face view of a piece of fur ornamented according to my invention.

Similar letters indicate corresponding parts. 35 In the drawings, the letter A designates my clamp, which consists of a fixed jaw, *a*, secured to a foot, *b*, and of a movable jaw, *c*. Both jaws and the foot are, by preference, made of wood, but they may be made of any other suitable material, and the movable jaw swings on a pivot, *d*, which passes through it near one of its ends and is secured in the fixed jaw. When the movable jaw is turned down to its closed position, Fig. 2, its loose end catches in a hook, *e*, 40 which extends from the fixed jaw. The inner surface of the movable jaw is lined with sand-paper *f* or other equivalent rough material.

The fur or pelt which is to be ornamented is placed upon the fixed jaw *a* and then the movable jaw *c* is closed down, as shown in Fig. 1. 45 In closing down said movable jaw the hairs of the pelt are drawn down by sand-paper *f* and

firmly retained between the jaws and a portion of the skin of the pelt is exposed, so that tuft *g* of fur, can be readily secured to said skin, and that when the pelt is removed from the skin its hairs reassume their original position, so as to embrace the tufts *g* and conceal the slips of skin *h*, by means of which said tufts are secured to the pelt.

In ornamenting a pelt of a dark color I use tufts of white or other light-colored fur, and a very beautiful effect is produced.

In carrying out my invention it is very essential that the tufts of fur shall be secured to the bare skin of the pelt without disarranging the hairs thereof, and it is therefore necessary to provide some means for exposing the bare skin of the pelt and retain it while thus exposed in a convenient position for attaching the slips of skin *h* of the tufts *g*. This object I have accomplished by my clamp A, which enables me to sew the tufts *g* to the skin of the pelt without disarranging the hairs of said pelt.

I am aware that furs have been ornamented by attaching the stems of feathers directly to the pelt and allowing the feathered tips to project over the surface of the fur. This I do not claim.

I am also aware that pieces of fur of different colors have been combined.

What I claim as new, and desire to secure by Letters Patent, is—

1. The within-described method for ornamenting fur by attaching to its skin tufts of fur of a different color, the hairs of the body fur or pelt being pressed out of the way so as to expose the bare skin and allow of securing the tufts thereto without injuring or disarranging its hairs, as set forth.

2. The clamp A, composed of the fixed jaw *a*, the movable jaw *c*, which is provided at one end to the fixed jaw and lined on its inner surface with sand-paper or other equivalent rough material, substantially as and for the purpose shown and described.

In testimony whereof I have hereunto set my hand and seal in the presence of two subscribing witnesses.

EDOUARD BERTRAND. [L. S.]
